US0D1088417S

(12) **United States Design Patent** (10) Patent No.: **US D1,088,417 S**
(45) Date of Patent: **** Aug. 19, 2025**

(54) **HEADBAND**

(71) Applicant: **Rezon Limited**, Stanley (GB)
(72) Inventor: **Judith Louise McMinn**, Tyne and Wear (GB)
(73) Assignee: **Rezon Limited**, Stanley (GB)

(**) Term: **15 Years**

(21) Appl. No.: **29/790,779**

(22) Filed: **Dec. 14, 2021**

(30) **Foreign Application Priority Data**

Jun. 16, 2021 (GB) 6142754

(57) **CLAIM**

The ornamental design for a headband, as shown and described.

DESCRIPTION

FIG. 1 is a front view of a headband showing the new design.
FIG. 2 is a rear view thereof.

FIG. 3 is a left side elevational view thereof; and,
FIG. 4 is a right side elevational view thereof.

The broken lines in the drawings depict environmental subject matter that forms no part of the claimed design.

1 Claim, 4 Drawing Sheets
